UNITED STATES PATENT OFFICE

LEE B. GREEN, OF LAKWOOD, OHIO, ASSIGNEE TO THE BORDEN COMPANY, OF WARREN,
OHIO, A CORPORATION OF OHIO

LUBRICATING SYSTEM FOR WASHING MACHINES

Application filed January 9, 1929. Serial No. 331,377.

This invention relates to improvements in lubricating means for washing machines, particularly washing machines of the submerged oscillator type. However, the invention in some of its aspects is susceptible of wider use.

One of the objects of the invention is the provision of means for carrying lubricant along a horizontally arranged connecting rod to the mechanism at one end thereof.

Another object is the provision of an oil cavity in the upper surface of a horizontal oscillating gear sector, and the lubrication therefrom of mechanism associated with said sector.

Another object is the provision of means for taking oil from a sump and depositing it in a channel in the upper surface of a horizontal connecting rod during the reciprocation of the latter, said means being associated with the driving means of the connecting rod.

Another object is the provision of means for utilizing a longitudinally moving control shaft for the production of hydraulic pressure to force lubricating oil to points requiring lubrication.

Other objects and features of novelty will appear as I proceed with the description of that embodiment of the invention which, for the purposes of the present application, I have illustrated in the accompanying drawings in which:

Fig. 1 is a vertical sectional view illustrating a driving mechanism for a washing machine and wringer, embodying my invention;

Fig. 2 is a plan view of the operating mechanism with the upper section of the gear casing removed;

Fig. 3 is a detail sectional view taken substantially on the line 3-3 Fig. 1; and

Fig. 4 is a fragmentary detail view on a larger scale, of a portion of the power shaft, this view showing an oil thrower which may be employed in connection with the invention.

In the drawings I have illustrated the invention as applied to a washing machine of the submerged oscillator type, a fragment of the tub being shown at 10. At the cen-

ter of the tub there is a casting 11 which is formed hollow in order to receive the shaft 12, by means of which the oscillator (not shown) is driven.

One end of the gear casing, which is split into upper and lower sections 13 and 14, is attached to the casting 11 by studs 15. The lower end of the shaft 12 is rotatably supported in the casing section 14 by a roller bearing 16, or otherwise. Above this bearing 16 the shaft has keyed thereto a pinion 17 which meshes with a toothed sector 18 that is mounted to oscillate upon a stud 19 anchored in the casing section 14. The upper surface of the sector 18 is inset to form a shallow oil cavity 20. A pivot pin 21 extends upwardly from a more or less central point of the sector 18, and constitutes the connection between the sector and the connecting rod 22. In the sector 18 there are two drilled passages 23 and 24 leading from the oil cavity 20 downwardly at an angle to the bearing surfaces of the pins 19 and 21, respectively.

In the opposite side walls of the casing section 14, below the level of the connecting rod 22, I mount a power shaft 25 that is adapted to be attached directly or indirectly to a driving motor (not shown). Within the casing this shaft carries a worm 26 which meshes with a worm wheel 27. The latter has a depending hub 28 which is rotatably supported in a bushing 29 carried by a suitably formed portion of the casing section 14. The thrust produced by the weight of the worm wheel and superposed parts is taken upon a washer 30.

The worm wheel 27 is provided with an upwardly extending projection in the form of a crescent 31, which is preferably cast integrally with the worm wheel. The crescent is smooth upon both of its side surfaces. It is surrounded by an internal gear formed upon an eccentric 32, the center of the gear being offset from the center of the eccentric, as clearly shown in Fig. 2. Within the smooth inner wall of the crescent 31 there is a pinion 33 that is provided with an extension hub bearing externally in a counterbore 34 of the worm wheel. The pinion 33 meshes with the gear teeth on the eccentric 32. Cou-

sequently, as it rotates, the eccentric is turned upon the crescent 31 thereby revolving about the center of the crescent to vary the eccentricity of the eccentric. An eccentric strap 35 surrounds the eccentric 32, being formed preferably integral with the connecting rod 22.

The pinion 33 normally rotates with the worm 27. It is capable of limited rotation with respect to the worm wheel, however, and this relative rotation is brought about by a sliding control shaft 36 provided with spiral grooves 37 that cooperate with threads 38 on the internal surface of the hollow pinion 33. The control shaft 36 also has rectilinear grooves 39 which slidably receive corresponding splines in the hub of the worm wheel 27. Hence, as the shaft 36 moves up and down in the worm wheel 27, its spiral thread connection with the pinion 33 produces rotation of the latter with respect to the worm wheel.

Below the worm and worm wheel 26 and 27, the casing section 14 is depressed to form an oil sump 40. From this sump one or more ducts 41 conduct oil to ports 42 extending through the bushing 29. The inner surface of the bushing is preferably provided with one or more oil grooves 43 communicating with the ports 42. Below the casing section 14 there is an extension casing 44 into which the bushing 29 and the hub 28 of the worm wheel protrudes. This extension casing is preferably secured to one of the locks 45 of the machine by means of a hook bolt 46 or the like. One side of the casing 44 is provided with a removable plate 47 carrying a boss 48 in which is formed a bearing for a shaft 49 provided with a packing 50. On the inner end of the shaft 49 is a pinion 51 which meshes with a rack 52 that is provided with a flat rear face engaging a flattened inwardly extending portion 53 of the casing 44. By the latter means a slide bearing for the rack is provided opposite the pinion 51, and the rack is prevented from turning. The rack is made from tubular material, and within its bore rotatably receives a rod 54, which is threaded at its upper end into the bottom control shaft 36. The lower end of rod 54 has pinned thereto a collar 55. The rack is, therefore, carried by the shaft 36, but does not rotate with that shaft. The lower end of the casing 44 may be closed by a welch plug 56 or other suitable means.

On the upper side of the casing section 14 I mount a hollow wringer post 57 having a flanged base 58 secured to the casing section 13 by screws 59 or the like. Inside the post 57 there is a tubular shaft 60 which is mounted for rotation, its lower bearing 61 only being here illustrated, and being formed preferably integral with the upper casing section 13, and carrying packing 62. The latter is held in place preferably by a pressed-in annular plug 63. The bore of the tubular shaft

60 is of sufficient diameter to permit the shaft 36 to slide freely therein. At its lower end the shaft 60 has welded, or otherwise secured thereto, a plate or collar 64, in which is mounted a depending pin 65 that takes into a bore 66 in the crescent-shaped projection 31 of the worm wheel. It is by this means that the shaft 60 is driven. At a point above the furthest upward travel of the shaft 36, the shaft 60 is closed, as indicated at 57, and at its upper end this shaft may have operative connection with a wringer mechanism (not shown). The plate 64 overlies portions of the eccentric 32 and of the eccentric strap 35, and hence holds them in proper position. This plate, together with the end of the shaft 60, also engages the pinion 33 and prevents its upward movement. Oil ports 68 are drilled through the hollow shaft 60, connecting the interior thereof with the surface of bearing 61 for the lubrication of the latter.

On the shaft 25, to one side of the worm 26, I secure an oil thrower 69. As here illustrated, it comprises a sleeve 70 having at one end a radial flange which, at intervals, has cut out and bent up portions forming oil throwing blades 71.

When it is desired to operate the machine, the shaft 25 is caused to rotate, as by means of a suitable electric motor. The worm wheel 26 is thus rotated at a considerably decreased rate of speed. The eccentric 32, which is locked in position upon the worm wheel by means of the intermeshing teeth on the eccentric and on pinion 33, then revolves and reciprocates the connecting rod 22, which oscillates sector 18 and thereby the agitator shaft 12. At the same time, rotation is imparted to the wringer shaft 60 through the intermediacy of the pin 65 and the plate 64. The position of the eccentric in Fig. 2 is that which it occupies when it is set for the maximum stroke of the agitator. Now should it be desired to reduce the length of stroke, the shaft 49 is rotated manually by any suitable connections to cause pinion 51 to turn anti-clockwise, as viewed in Fig. 1, and thereby to raise the rack 52 and the control shaft 36. This may be done while the machine is in operation. The pinion 34 is thereby rotated in a clockwise direction, as viewed from the top, and the eccentric 32 is made to travel around the crescent 31 by virtue of the intermeshing teeth on the pinion and on the eccentric.

In Fig. 2 I have marked the axis of pinion 36 and of the worm wheel 27 with the letter "A", and the centers of the crescent 31 and eccentric 28 with the letters "B" and "C", respectively. The point A remains stationary at all times. The point B revolves about the point A during the operation of the machine, the radius of rotation remaining constant at all times. The point C also revolves about the point A during the opera-

tion of the machine, but its radius may be varied by the operator, and when the radius is thus varied, the point C moves in an arc of a circle about the point B. With these three points in alignment, as shown, the throw of the eccentric is at its maximum. Its throw is decreased gradually as the point C moves in its circle toward the point A, and when it arrives at the point A the eccentricity of the eccentric becomes zero, and the connecting rod receives no motion whatever. As the crescent 31 is fixed upon the worm wheel 27, the pin 65 revolves constantly in a given circle regardless of the adjustment of the eccentric, and, consequently, the shaft 60 turns at a constant speed at all times when the motor of the machine is running.

The casing extension 44 and the lower part of the casing section 14, including the sump 40, are filled with oil. Oil is thrown upwardly by the rapidly rotating oil thrower 69, forming a mist which thoroughly lubricates all of the exposed working parts in that vicinity. Part of the oil thus thrown upward drops into the upper channel-shaped surface of the connecting rod 22, and flows to the outer end thereof and then through a hole 72 in the connecting rod into the shallow cavity 20 in the upper surface of the sector 18. The ducts 23 and 24 conduct oil from this cavity into the bearings around the stud 19 and the pivot 21. The overflow from the sector 18 lubricates the pinion 17 and the bearing 16 at the lower end of shaft 12. Excess oil drains back along the bottom of the casing section 14 into the sump 40, and hence there is a continuous circulation of oil to and from the oscillator mechanism at the outer end of the connecting rod.

The bearing for the hub 28 of the worm wheel 27 is thoroughly lubricated by oil conducted to it through the passages 41, ports 42 and grooves 43. Any leakage from this bearing finds its way into the oil-tight casing below. The latter should be well filled with oil. When the control shaft is depressed by the operator, pressure is put upon the oil in the casing extension 44, and oil is forced upwardly along the control shaft 36 into the hollow shaft 60. This action will be delayed somewhat owing to the fact that the flow of the oil between the control shaft and the worm wheel 27 and between the shaft and the pinion 33 is considerably restricted. This upward flow of oil will more or less fill the cavity in shaft 60, and because of the restricted passages along the control shaft the return of the oil from the cavity in shaft 60 to the casing extension 44 by gravity will be very slow. In the meantime the operator is likely to again raise the shaft 36, and as the flow of oil out of the cavity in shaft 60 is restricted, oil pressure will be built up in the shaft 60 by the ascent of the shaft 36, and this pressure will be effective to force oil

through the openings 68 in the bearing 61. Upward flow out of that bearing is prevented by the packing 62.

Having thus described my invention, I claim:

1. In combination, a vertical drive shaft, a horizontal connecting rod, means for converting the rotation of said shaft into reciprocating motion of said rod, driven mechanism operatively connected with the opposite end of said rod, said rod having a longitudinal channel in its upper surface, and means associated with the driving means for said connecting rod for depositing oil in said channel, whereby it is conducted to said driven mechanism.

2. In combination, a vertical shaft, gearing connections for driving said shaft, a horizontal connecting rod arranged above said gearing connections, means for converting rotation of said shaft into reciprocating motion of said rod, an oil sump adjacent said shaft beneath said gearing, driven mechanism operatively connected with the opposite end of said rod, said rod having a longitudinal channel in its upper surface, said gearing comprising means for throwing oil from said sump into said channel.

3. In combination, a vertical shaft, gearing connections for driving said shaft, a horizontal connecting rod arranged above said gearing connections, means for converting rotation of said shaft into reciprocating motion of said rod, an oil sump adjacent said shaft beneath said gearing, driven mechanism operatively connected with the opposite end of said rod, said rod having a longitudinal channel in its upper surface, said gearing comprising means for throwing oil from said sump into said channel, whereby oil is conducted to said driven mechanism, and means for returning surplus oil from said driven mechanism to said sump.

4. In combination, a vertical shaft, a worm wheel fixed to said shaft, a power shaft carrying a worm meshing with said worm wheel, a horizontal connecting rod having a channel in its upper surface, means above said worm wheel for converting the rotation of said vertical shaft into reciprocations of said rod, a sump beneath said power shaft, a driven mechanism operatively connected with the opposite end of said connecting rod, said power shaft comprising means for throwing oil from said sump into said channel.

5. In combination, a vertical shaft, a worm wheel fixed to said shaft, a power shaft carrying a worm meshing with said worm wheel, a horizontal connecting rod having a channel in its upper surface, means above said worm wheel for converting the rotation of said vertical shaft into reciprocations of said rod, a sump beneath said power shaft, a driven mechanism operatively connected with the

opposite end of said connecting rod, said power shaft comprising means for throwing oil from said sump into said channel and onto said motion converting means.

5 6. In combination, a vertical shaft, gearing connections for driving said shaft, a horizontal connecting rod arranged above said gearing connections, means for converting rotation of said shaft into reciprocating motion

10 of said rod, an oil sump adjacent said shaft beneath said gearing, driven mechanism operatively connected with the opposite end of said rod, said rod having a longitudinal channel in its upper surface, and a rotary oil

15 thrower associated with said gearing and extending downwardly into said sump for throwing oil from said sump into said channel.

7. In combination, a vertical shaft, a worm 20 wheel fixed to said shaft, a power shaft carrying a worm meshing with said worm wheel, a horizontal connecting rod having a channel in its upper surface, means above said worm wheel for converting the rotation

25 of said vertical shaft into reciprocations of said rod, a sump beneath said power shaft, a driven mechanism operatively connected with the opposite end of said connecting rod, and an oil thrower attached to said power

30 shaft adjacent said worm for throwing oil from said sump into said channel.

8. In combination, a vertical shaft, a worm wheel fixed to said shaft, a power shaft carrying a worm meshing with said worm

35 wheel, a horizontal connecting rod extending above said power shaft having a channel in its upper surface, means for converting the rotation of said vertical shaft into reciprocations of said rod, a sump beneath said

40 power shaft, a driven mechanism operatively connected with the opposite end of said connecting rod, said power shaft comprising means for throwing oil from said sump into said channel.

45 In testimony whereof, I hereunto affix my signature.

LEE B. GREEN.
